UNITED STATES PATENT OFFICE

CHARLES BOHLEN, JR., OF NEW YORK, N. Y., ASSIGNOR TO INTERNATIONAL MOTOR COMPANY, OF NEW YORK, N. Y., A CORPORATION OF DELAWARE

LEVELING MECHANISM FOR FIRE LADDERS

Application filed September 5, 1929. Serial No. 390,504.

The present invention relates to vehicular fire fighting apparatus and embodies, more specifically, an improved mounting for fire ladders by means of which the ladder may be adjusted universally with respect to the vehicle upon which it is mounted.

It frequently happens that the truck upon which a fire ladder is mounted cannot be manœuvred to a relatively horizontal position and, as a result, the truck must lie at an angle to the horizontal, and to the portions of the building to which access is desired. This not only imperils the use of the ladder, but also imposes severe stresses thereupon and frequently gives rise to damaging results.

An object of the invention, therefore, is to provide a device for leveling the ladder and turntable carried upon a vehicle.

A further object is to incorporate a leveling mechanism of the above character in a ladder elevating and turntable orienting construction of an improved form, such elements being incorporated without impairing the serviceability of the elevating and orienting mechanism and being conveniently disposed with respect thereto.

A further object of the invention is to provide a device for automatically leveling a ladder of the above type.

Further objects, not specifically enumerated above, will be apparent as the invention is described in greater detail in connection with the accompanying drawings, wherein:

Figure 1 is a view in side elevation, cut away and partly in section showing a ladder elevating mechanism carried by a turntable and provided with means for varying the position of the platform, turntable and ladder with respect to the horizontal.

Figure 2 is a view in section, taken on line 2-2 of Figure 1, and looking in the direction of the arrows.

Figure 3 is a view showing a modified construction, wherein an automatic means for varying the level of the ladder is provided.

Figure 4 is a schematic view showing the wiring diagram incorporated in the construction shown in Figure 3 for controlling the direction of fluid pressure upon the leveling piston.

Referring to the above drawings, *a* designates a trailer frame upon which an annular ring *a'* is carried. This ring is journaled upon a fifth wheel *a''*, carried by a tractor, by means of ball bearings *a'* and teeth *a''* are provided in the periphery of the ring *a'* to enable the turntable to be oriented properly. A bearing ring *a''* is journaled on the ring *a'* and carries a bracket *a''* having a saddle portion *a''*. Upon the saddle portion, bearings *b* are provided and a turntable *c* is supported on the bearings through a bearing plate *d*. The bearing plate is formed with a curvature, the center of which coincides with the axis of an elevating shaft *c'* which constitutes a portion of the elevating mechanism and extends within a gear box *c''*. Power is supplied to the mechanism within housing *f* by means of suitable mechanism within a housing *r*, shown in Figure 1 of the drawings.

Gear box *c''* is formed with a boss *c''* having a bearing surface and an auxiliary housing *f* is provided with extension *f'* having a flange *f''* for engaging the bearing surface *c''*. An annular retaining plate *c''* is carried by the gear box and engages the flange *f''* to permit rocking movement of the gear box *c''* with respect to the relatively stationary housing *f* without destroying the continuity of the housing for the elevating mechanism. The gear box is mounted upon the ladder pivot shaft *e'* by means of arms *c''* having reinforcing webs *c''*. Although housing *f* rotates about a vertical axis, it does not partake of the rotative movement of the platform *c* and gear box *c''* necessary to level the ladder, and the connection last described permits such relative rotation between the gear box and housing. It will be understood, of course, that the leveling axis passes through the housing *f* and shaft *c'*, the gearing arrangement in the box being similar to that shown in the copending application Ser. No. 390,503, filed September 5, 1929.

The ladder *e* is mounted upon A-brackets *e'* carried upon the platform *c* and is elevated by means of the mechanism carried within the gear box *c''* and housing *f*, together with the arms *e''* and links *e'''*.

The bearing member d is reenforced by suitable webs d' and is formed with laterally extending cylindrical portions d^2 for engaging the bearings b . U-brackets g are secured to the upper portions of the laterally extending sides d^2 of the bearing member d , and thus secure the bearing member to the saddle and prevent dislodgment therefrom.

A worm segment h is carried by the platform c and is engaged by a worm h' carried upon a bracket h^2 upon the ring a^4 . This bracket is formed with spaced standards h^3 within which a shaft h^4 is journaled, the worm h' being splined to the shaft h^4 . A bevel gear h^5 is splined to the shaft h^4 and engages a bevel pinion h^6 which is mounted upon a vertically disposed, manually operable shaft h^7 . Shaft h^7 is journaled in the bracket h^2 and h^8 and in a bracket i carried upon the bracket h^2 . Hand wheel h^9 enables the shaft h^7 to be turned and thus varies the position of the segment h and platform c with respect to the ring a^4 .

A second bearing member j is carried by the platform c and engages a bearing seat j' upon the ring a^4 . This seat j' and bearing member j have a bearing surface, the axis of which coincides with that of the shaft c' , similarly to the bearing surface upon the bearing member d . It will be seen, therefore, that the turntable and elevating mechanism is adequately supported upon the ring a^4 which may be oriented with respect to the frame a .

In order that the ladder may be automatically leveled, a modified construction is shown in Figures 3 and 4. In this form, the worm segment h and related manually operating mechanism is replaced by downwardly extending arms k , carried by the turntable c . Between these arms, a cylinder l is carried oppositely extending arms l' on the cylinder engaging elongated slots k' in the arms k .

A rod m is secured to the sides of the frame a at m' and a piston m^2 is secured to the rod m and is slidably carried within the cylinder l . Flexible pipe lines n and n' communicate with the cylinder l upon opposite sides of the piston m^2 and carry a fluid under pressure from a pump o driven by a reversing motor o' . Upon rotation of the motor in one direction, a fluid pressure is exerted upon one side of the piston, while upon rotation in the opposite direction, a fluid pressure is directed on the opposite side of the piston. This results in the movement of cylinder l and arms k in the appropriate direction and the platform c is thus leveled by the proper movement of the arms.

The lowest rung p of the ladder is preferably of hollow metal and carries a sealed tube q having terminals q' , q^2 , and q^3 . A globule of mercury q^4 is sealed in the tube and is of sufficient size to connect contact q^3 with either of contacts q' or q^2 , depending upon the slope

of the tube. If the ladder and tube are level, the globule of mercury will rest in a recess q^3 and the motor o' will not be energized. If the ladder is not level, contact q^3 will be automatically connected with either contacts q' or q^2 and the motor will be driven in the desired direction to move arms k to a vertical position.

While the invention has been described in connection with the specific construction shown in the accompanying drawings, it is not to be limited, save as defined in the appended claims.

I claim as my invention:

1. A fire ladder operating means comprising a turntable, a ladder support carried by the turntable, a ladder on the support, means on the support to elevate the ladder, an arm carried by the support, means to exert pressures in opposite directions on the arm, a motor for operating the last named means, reversing contacts on the ladder and connected with the motor, and means controlled by the level of the support for closing certain of the contacts.

2. A fire ladder operating means comprising a turntable, a ladder support carried by the turntable, a ladder on the support, means on the support to elevate the ladder, an arm carried by the support, means to exert pressures in opposite directions on the arm, and means controlled by the inclination of the support to cause the last named means to exert a pressure on the arm.

3. A fire ladder operating means comprising a turntable, a ladder support, a ladder on the support, a ladder elevating means on the support, a cradle on the turntable having a curvature about the axis of the ladder elevating means, a bearing member on the support and engaging the cradle, a second cradle and bearing on the turntable and support respectively, and having curvatures about the axis of the elevating means, and means to vary the inclination of the support with respect to the turntable.

4. A fire ladder operating means comprising a turntable, a ladder support, a ladder on the support, a ladder elevating means on the support, a cradle on the turntable having a curvature about the axis of the ladder elevating means, a bearing member on the support and engaging the cradle, and means to vary the inclination of the support with respect to the turntable.

5. A fire ladder operating means comprising a turntable, a cradle carried by the turntable, a ladder support, a bearing member on the support engaging the cradle, a ladder on the support, means on the support to elevate the ladder, and means to move the support and bearing member with respect to the cradle.

6. A fire ladder operating means comprising a turntable, a ladder support carried by

the turntable, a ladder on the support, means on the support to elevate the ladder, and means to vary the inclination of the support with respect to the turntable.

7. In a fire ladder operating means comprising a turntable having a ladder support and ladder pivoted on the support and lying in a normally lowered position, means on the support to elevate the ladder, means to mount the support upon the table for movement in a plane at right angles to the plane of the table, a worm segment on the support in a plane parallel to the pivot axis of the ladder, a worm on the turntable engaging the segment, and means to rotate the worm.

15 This specification signed this 3rd day of August, A. D. 1929.
